E. HOPKINSON

MANUFACTURE OF TIRE CASINGS

Filed Nov. 18, 1922

MANUFACTURE OF TIRE CASINGS.

Application filed November 18, 1922. Serial No. 601,692.

To all whom it may concern:

Be it known that I, ERNEST HOPKINSON, a citizen of the United States, residing at New York city, county of New York, and

5 State of New York, have invented certain new and useful Improvements in the Manufacture of Tire Casings, of which the following is a full, clear, and exact description.

10 This invention relates to the manufacture of tire casings, in particular their vulcanization.

It has been found desirable in curing casings, especially those built on cores, to partially cure them without exerting a compacting pressure on their walls, and subsequently to completely cure the casings while maintaining a high compacting pressure thereon. This invention concerns such a process and

20 aims to provide a new and improved method and apparatus for carrying on the same. More particularly, it aims to eliminate a difficulty, condensation, had with previously proposed practices, in the first or partial

25 curing stage, the steam heretofore employed often condensing and causing blemishes, or disconfigurations, objectionable to the trade.

With the illustrated embodiment in mind and without intention to limit more than

30 is required by the prior art, the invention, briefly, consists in partially vulcanizing the casings with products of combustion which are supplied to a press containing a stack of loosely assembled molds and tires on

35 cores, thereafter completing the vulcanization of the casings with a moist, humid heating medium, such as steam, and with the sections of the mold clamped together under great pressure.

40 A preferred embodiment of the invention is illustrated in the accompanying drawings, in which:—

Fig. 1 is an elevation partly in section, diagrammatically illustrating apparatus for

45 carrying on the process;

And Fig. 2 is a cross-section through a mold, illustrating a straight-side casing in the condition the parts are during partial curing.

50 According to my invention, products of combustion intermingled with air to regulate the temperature of the mixture are conducted through a duct 1, provided with a suitable valve 2, into a press 3, and exhausted therefrom at a suitable speed

through a valve-controlled pipe 4, the inlet and outlet being located as desired to permit good circulation of the heated gases and maintenance of the vulcanizing temperature within the press. The press 3 may be of any suitable type, preferably having a mold moving means, or platen, 5, between which and the head 6, sectional molds 7 may be clamped, when desired, upon the walls of casings 8 mounted on cores 9. A valve-controlled inlet 10 and a valve-controlled outlet 11 are provided for introducing steam into the press, when desired.

As it is desirable to relieve the casings of a substantial compacting pressure during the partial curing treatment, the molds are loosely assembled and stacked upon one another in a press at the outset of the curing treatment. While this may be done variously, I preferably insert collapsible lead

70 pellets 12 between either, or both, the sections of the mold and the core, as illustrated.

For the combustion products, or gases, I preferably provide a furnace 13, having an elongated combustion chamber 14, at one end of which is located an oil-burner 15, of any suitable type. Usually, this comprises an air-line 16 and an oil-line 17. Air for combustion may be supplied through orifices 18 around the nozzle of the burner and also through a damper 19, controlling the passage of air into a pit 20 filled loosely with fire-brick, openings 21 being provided to allow the air to enter the combustion chamber 14. The combustion products are removed from the rear of the furnace through a relatively large pipe or duct 22, provided with a damper 23, between which and the press is located an air-inlet 24, and a suction-fan 25. By suitable regulation of the dampers 23 and 26, the latter in the air-inlet, the suction device 25 may be relied upon to properly supply combustion products to the main 27. From the main 27, branches, such as the duct 1, may be provided for each of a plurality of presses, if desired, and thereby the latter supplied with combustion products in an economical manner.

55 In operation, after loosely stacking the sectional molds 7 in a press, the latter is closed, as shown in Fig. 1, but without operating the platen, or ram, 5, to clamp the molds together. Thus, the casings in the sectional molds are substantially free of any

substantial compacting pressure even when the collapsible device, or lead pellets, 12, are made short enough in length to allow the mold sections to warmingly engage their 5 rubber walls, as is desirable in some cases. The products of combustion from the furnace are then turned into the press chamber and passed therethrough to partially vulcanize the composition of the casings to the 10 desired extent. The molds are comparatively cool at the outset of the operation and if steam were turned into the heater at this time, condensation would certainly occur and cause blemishes on parts of the casings, 15 especially the pockets in the lower sections of the molds. By supplying products of combustion which are entirely, or almost entirely, free of moisture, this difficulty is avoided and the process made practical of 20 performance in a vulcanizing press.

When the treatment with combustion products, or gases, has partly vulcanized the casings to the desired extent, the molds are closed so as to exert a powerful pressure 25 upon the casings. This is done simply by operating the ram 5, in which case, of course, the collapsible lead pellets 12, if employed, are crushed, their ductile metal flowing into recesses, or pockets, 28, of any 30 suitable configuration, provided in the molds. Thereafter, the casings are completely vulcanized by supplying steam through the inlet 10 to the press, either at a high pressure, around 35 or 40 pounds, if 35 steam alone is to be used as the final heating medium, in which case the valve-controlled lines 1 and 4 are cut off, or by supplying steam at about atmospheric pressure and commingling it with combustion products to make the latter humid and a better 40 conductor of heat to the molds, in which case it is advantageous to introduce the steam adjacent the branch or duct 1.

From the foregoing, it will be seen that I 45 have provided an extremely simple and practical device for carrying on a two-stage method of curing, sometimes known as the "set cure", in a French type of press that is in widespread use. The molds are only 50 required to be handled once and the curing operations, or manipulations, are practically

as simple as in the old straight cure procedure.

It will be obvious that many changes may be made in the procedure and apparatus 55 without departure from the principles underlying the same, and reference should therefore be made to the accompanying claims for an understanding of the scope of the invention.

Having thus described my invention, what I claim and desire to protect by Letters Patent is:—

1. A method of curing tire casings in sectional molds which consists in, loading a 65 vulcanizing press with tire casings in molds whose sections are separated, subjecting the substantially free casings at first to the products of combustion from a furnace thereby partially curing them, and thereafter to steam while maintaining a compacting pressure on the casings and completely curing the casings.

2. A method of curing tire casings in sectional molds which consists in, loosely assembling tire casings on cores in sectional molds in a press, conducting products of combustion from a furnace and at a vulcanizing temperature through the press to partially cure the casings while the sections of the molds are collapsibly held separated, and finally completing the vulcanization of the casings with steam while pressing the mold sections together to exert a 75 compacting pressure on the casings.

3. A method of curing tire casings in sectional molds which consists in, stacking a plurality of sectional molds containing tire casings mounted on cores in a vulcanizing press and collapsibly supporting the 80 mold sections and cores, intermingling air with combustion gases to control the temperature of the mixture and conducting the mixture through a press to partially cure the casings, and subsequently closing the 85 molds compactly upon the casings and completing their vulcanization by supplying a humid heating medium to the press.

Signed at New York city, county of New York, and State of New York, this 16th 100 day of November, 1922.

ERNEST HOPKINSON.
